No. 722,215.

PATENTED MAR. 10, 1903.

E. W. DE RUSSETT.

COVER FOR VESSELS' HATCHWAYS.

APPLICATION FILED JUNE 9, 1902

NO MODEL.

FIG. 3.

FIG. 1.

FIG. 2.

FIG. 4.

The technical drawing illustrates a vertical assembly of four identical rectangular components, labeled A, B, C, and D from top to bottom. Each component features a central horizontal slot. On the left side of each slot, there is a vertical projection labeled 'B' at the top and 'a' at the bottom. On the right side of each slot, there is a vertical projection labeled 'C' at the top and 'd' at the bottom. Each of these four projections is secured with a small bracket and a screw, with the screw head labeled 'F'.

UNITED STATES PATENT OFFICE.

EDWIN W. DE RUSSETT, OF TYNEMOUTH, ENGLAND.

COVER FOR VESSELS' HATCHWAYS.

SPECIFICATION forming part of Letters Patent No. 722,215, dated March 10, 1903.

Application filed June 9, 1902. Serial No. 110,734. (No model.)

To all whom it may concern:

Be it known that I, EDWIN WILLIAM DE RUSSETT, civil engineer and naval architect, a subject of the King of Great Britain and Ireland, residing at Warden House, Tynemouth, in the county of Northumberland, England, have invented certain new and useful Improvements in and Relating to Covers for Vessels' Hatchways and Similar Openings, of which the following is a specification.

This invention relates to covers for vessels' hatchways and similar openings; and it has for its object to provide means for reducing the time occupied at present in opening and closing same and also to provide more durable means for rendering the hatch-covers practically or absolutely water-tight, whereby the vessel is rendered more seaworthy.

In carrying out this invention the hatch-covers are preferably made of steel or other similar material, either flat, corrugated, dished, or channeled. The covers may be made in one or more pieces, according to the size of the hatch and the strength or handiness of the available appliances for lifting or moving them.

The covers may be hinged at one or both ends or sides of the hatches. If the covers are hinged, they may rest when closed on the top edge of the coamings and they may be made to close water-tight around the edges by means of lap-joints consisting of strips of tarpaulin or other suitable material efficiently attached to the hatch-cover, for instance, by means of metal strips fixed by bolts and nuts or screwed pins or rivets to the edge of the cover and which are secured to the hatch-coaming by being pressed tightly against them by any suitable means or, as at present, by hatch-bars pressed against the tarpaulin by means of wedges bearing against cleats riveted to the coamings or by means of screws tapped into cleats and so pressing against the hatch-bars to secure the tarpaulin.

If the hatch-cover is in more parts than one, the joints between the parts may be made water-tight by causing the meeting edges of the said parts to overlap with india-rubber jointing inserted between the said edges, which are then pressed together in any suitable manner. The joints are, however, preferably made water-tight by means of strips

of tarpaulin secured in a similar manner to that hereinbefore described for securing the strips of tarpaulin at the outer edges of the cover to the hatch-coaming, except that in this instance the tarpaulin is laid up and over vertically-projecting meeting edges of the parts of the cover and is secured at each end of the said meeting edges—say by the bar which secures the tarpaulin against the coaming.

The hereinbefore-described construction of cover and appliances for securing same are suitable for hatches in which the top of the coaming is sufficiently raised above the deck to enable the hereinbefore-described lapped joints to be made.

I will now refer to the accompanying drawings, which illustrate my invention.

Figure 1 is a transverse sectional elevation of the improved hinged hatch-cover. Fig. 2 is a plan of Fig. 1. Fig. 3 is an enlarged section of the hinged joint, also showing the means for making the water-tight joint between the cover and the coamings. Fig. 4 is a section showing the means for making the water-tight joint between the meeting edges of a hatch-cover made in more parts than one. Fig. 5 is a sectional elevation showing the end of the joint shown in Fig. 4.

Referring to Figs. 1, 2, and 3, A is the hatch-cover, having stiffening-bars *a* of bulb-angle section. *a'* are the hinge-joints, four being shown on the hatch illustrated. The hinge-joints *a'* are formed by brackets *B* *B'*, fixed, respectively, to the bulb-angle stiffener *a* of the cover and the side of the coaming *C*. These brackets are connected by a hinge-pin *b*, which is set away from the coaming *C*, as shown, to allow clearance for the overlapping joint between the hatch-cover and the coaming.

Referring now to the overlapping joint, it comprises an angle-iron strip *A'*, attached to the edge of the cover *A*, with one flange *a'* depending, while the other, *a''*, rests on top of the coaming *C*. A strip of waterproof canvas or similar waterproof flexible material *D* is attached to the depending flange *a'* either inside or out all around the hatch-cover. In the drawings this waterproof strip is shown as attached inside the flange *a'* by means of an iron strip or bar *d*, clamped to the flange upon the strip *D* by means of bolts and nuts *d'*.

This waterproof strip D is of such width that it can be passed down within cleats, such as E, secured to the sides of the coaming, where the waterproof strip is clamped by means of an iron battening-bar e and wooden wedges e'. Any other suitable means for securing the edge of the waterproof strip D in a watertight manner against the coaming may be employed. For instance, it may be secured by means of screws tapped into the cleat and serving when screwed up to press against the hatch-bars, and thus secure the tarpaulin. By arranging the overlapping joint as described the usual molding c' around the hatch-coaming may be used.

The hinged cover when closed will generally be heavy enough to be kept in position by its own weight; but in practice it may be found necessary to provide means for preventing the cover from being lifted by rough seas. For this purpose hinged or toggle bolts and nuts, such as shown at F F, Figs. 1 and 2, are preferably used to keep the covers down when closed; but any other suitable devices may be used for this purpose. Suitable rests are provided to support the cover when open. These are not shown in the drawings.

The hinged covers may be lifted by any suitable means, such as a derrick and tackle working off the nearest mast, or a worm and quadrant acting at or near the hinged end may be used.

Referring now to Figs. 4 and 5, which illustrate the means for making the water-tight joint between the meeting edges of the hatch-cover made in more parts than one, A³ A⁴ are two portions of a hatch-cover. G' and G² are two bulb-angles. The bulb-angle G' is mounted at the edge of the part A³, while the bulb-angle G² is mounted on the adjoining edge of the part A⁴. The bulb-angle G' is fixed so as to extend beyond the meeting edges of the parts, while the angle G² is set back a short distance from the edge of the part A⁴, thus providing an overlapping joint, as shown. D' is the strip of tarpaulin, fixed to the bulb-angle G' by bolts and nuts with a clamping-strip g and adapted when the parts are together to be passed up over the projecting meeting edges of the bulb-angles G' G², being then secured on the other side of the joint by means of clamping-bars and wedges g' g², secured between the bulb-angle G² and a lug or lugs g³, fastened to the hatch-cover A⁴. This is clearly shown in Fig. 4. In order that the waterproof strip D' may be properly secured at the ends, it is passed over the edge of the hatch-cover and secured against the coaming C by battens and wedges, as shown at h, Fig. 5.

The various means for securing the covers in place may be formed integrally with the covers or coamings or they may be separate therefrom. The toggle-bolts hereinbefore referred to are preferably hinged to cleats of a special pattern fixed to the coamings, or they

may have a rounded boss at the end of the bolt, which passing through a conical or enlarged hole—say in a lug or cleat—will allow the bolt to have play and so serve the same purpose as a hinge.

What I claim as my invention, and desire to secure by Letters Patent, is—

1. The improvements in and relating to covers for vessels' hatchways and similar openings comprising the combination of a hatchway, a cover thereto, a flexible waterproof strip having one of its edges attached to the edge of the cover, and means for clamping said waterproof strip tightly in a position overlapping the joining edges of the cover and hatchway, all substantially as and for the purpose set forth.

2. The improvements in and relating to covers for vessels' hatchways and similar openings comprising the combination of a hatchway, a cover thereto, a flexible waterproof strip, means for permanently fixing one edge of the said waterproof strip around the edge of the hatchway-cover, and means for detachably clamping the other edge of said waterproof strip to the hatchway-framing so that said strip overlaps the joining edges of the cover and hatchway, substantially as set forth.

3. The improvements in and relating to covers for vessels' hatchways and similar openings comprising the combination of a hatchway, a hatchway-cover in sections, a flexible waterproof strip attached to the edges of the cover and sections, projecting flanges forming edges to the adjoining edges of said sections, means for clamping the waterproof strip of flexible material around the joining edges of the cover and hatchway-coaming, means for clamping the flexible waterproof strip over the projecting flanges on the adjoining edges of the sections, means for clamping the ends of the waterproof strip which covers the adjoining edges of the sections to the hatchway-coaming, all substantially as and for the purpose set forth.

4. The improvements in and relating to covers for vessels' hatchways and similar openings comprising the combination of a hatchway, a coaming to said hatchway, a cover to the hatchway hinged to the coaming at one side, a downwardly-projecting flange around the edge of the cover, a strip of waterproof material attached to the downwardly-projecting flange, means for clamping the waterproof strip of flexible material against the coaming so as to form a water-tight joint therewith, all substantially as set forth.

5. The improvements in and relating to covers for vessels' hatchways and similar openings comprising the combination of a hatchway, a coaming to said hatchway, a cover to the hatchway, an overlapping joint between the hatchway-cover and the coaming formed by a downwardly-projecting flange upon the cover, a strip of waterproof flexible material passing all around the hatch-cover, means for

attaching one edge of said waterproof strip to the downwardly-projecting flange in the cover, means for clamping the other edge of said waterproof strip against the hatchway-
5 coaming and making a water-tight joint there- with when required, a hinge for the hatchway- cover formed by a bracket on the cover and a bracket on the coaming, said brackets being pivoted together and forming a hinged
10 joint clear of the flange upon the cover and the jointing means, all substantially as and for the purpose set forth.

6. The improvements in and relating to cov-
15 ers for vessels' hatchways and similar open- ings comprising the combination of a hatch- way, a coaming to said hatchway, a cover to the hatchway, an overlapping joint between the hatchway-cover and the coaming formed by a downwardly-projecting flange upon the
20 cover, a strip of waterproof flexible material passing all around the hatch-cover, means for attaching one edge of said waterproof strip to the downwardly-projecting flange in the cover, means for clamping the other edge of
25 said waterproof strip against the hatchway- coaming and making a water-tight joint there- with when required, a hinge for the hatchway- cover formed by a bracket on the cover and

a bracket on the coaming, said brackets be-
ing pivoted together and forming a hinged 30 joint clear of the flange upon the cover and the jointing means, means for clamping down the cover when in closed position, all substan- tially as and for the purpose set forth.

7. The improvements in and relating to cov- 35 ers for vessels' hatchways and similar open- ings comprising the combination of a hatch- way, a hatchway-coaming, a hatchway-cover hinged to the coaming, a flexible strip of wa- terproof material permanently attached at 40 one of its edges to the edges of the hatch- way-cover and overlapping the joining edges of the same and the hatchway-coaming when the cover is placed on the hatchway, and means for clamping the other edge of said 45 waterproof strip tightly in position when re- quired, all substantially as and for the pur- pose set forth.

In witness whereof I have hereunto signed my name in the presence of two subscribing 50 witnesses.

EDWIN W. DE RUSSETT.
